Des. 205,128
Patented June 28, 1966

205,128

SHOE SHINE STAND

Robert F. Newsom, 14345 E. Garvey,
Baldwin Park, Calif.

Filed Oct. 20, 1965, Ser. No. 87,624

Term of patent 14 years

(Cl. D9—2)

FIG. 1

FIG. 2

FIG. 3

FIG. 4

I claim:

The ornamental design for a shoe shine stand, as shown.
